ATTORNEY

UNITED STATES PATENT OFFICE.

JAMES GIBSON, OF BROOKLYN, NEW YORK.

DESIGN FOR A BEDSTEAD.

SPECIFICATION forming part of Design No. 27,315, dated July 6, 1897.

Application filed May 17, 1897. Serial No. 637,000. Term of patent 3½ years.

To all whom it may concern:

Be it known that I, JAMES GIBSON, a citizen of Great Britain, and a resident of Brooklyn, in the county of Kings and State of New York, have invented a certain new and useful 5 Design for a Bedstead, of which the following is a specification.

My design is especially adapted to the head-board and foot-board of a bedstead in which 10 such parts are made of cast-iron or other similar material; and it consists, essentially, of two scrolls of approximately S shape, horizontal bars connecting the said scrolls, and vertical bars connecting the horizontal bars, 15 as illustrated in the accompanying drawing, which represents a perspective view of a bedstead embodying the design.

In the drawing the letter A indicates the

S-shaped scrolls, B the horizontal bars connecting the same, and C the vertical bars 20 connecting the horizontal bars. At the point of juncture of the vertical and horizontal bars are knobs D, which may be ornamented in any desired way.

What I claim as my invention, and desire 25 to secure by Letters Patent, is—

The design for the head-board and foot-board of a bedstead, substantially as herein shown and described.

Signed at New York city, in the county of 30 New York and State of New York, this 29th day of April, A. D. 1897.

JAMES GIBSON.
